UNITED STATES PATENT OFFICE

117,305

DESIGN FOR A BOTTLE

Benjamin Paris, Wellington, New Zealand

Application February 16, 1939, Serial No. 83,026

Term of patent 14 years

To all whom it may concern:

Be it known that I, Benjamin Paris, a subject of the King of Great Britain and Ireland, residing in Wellington, in the Dominion of New Zealand, have invented a new, original, and ornamental Design for Bottles, of which the following is a specification, reference being had to the accompanying drawing, forming part thereof.

In the drawing,
Fig. 1 is a side elevational view of a bottle showing my new design, and

Fig. 2 is a sectional view taken along lines A—A of Fig. 1.

I claim:
The ornamental design for a bottle, as shown.
BENJAMIN PARIS.
